DESIGN FOR A CASKET

Karl F. Schmidt, Grand Rapids, Mich.

Application March 30, 1944, Serial No. 113,081

Term of patent 7 years

(Cl. D19—1)

To all whom it may concern:

Be it known that I, Karl F. Schmidt, a citizen of the United States, residing at Grand Rapids, in the county of Kent and State of Michigan, have invented a new, original, and ornamental Design for a Casket, of which the following is a specification, reference being had to the accompanying drawing, forming part thereof.

Fig. 1 is a side elevational view of a casket, showing my new design;

Fig. 2 is an end view thereof;

Fig. 3 is a top plan view thereof on a reduced scale.

I claim:

The ornamental design for a casket, substantially as shown.

KARL F. SCHMIDT.
